UNITED STATES PATENT OFFICE.

ALPHEUS W. ALTORFER, OF PEORIA, ILLINOIS, ASSIGNOR TO ALTORFER BROS. COMPANY, OF EAST PEORIA, ILLINOIS, A CORPORATION OF ILLINOIS.

IRONING MACHINE.

Application filed February 25, 1921. Serial No. 447,832.

To all whom it may concern:

Be it known that I, ALPHEUS W. ALTORFER, a citizen of the United States, a resident of Peoria, in the county of Peoria and State of Illinois, have invented new and useful Improvements in Ironing Machines, of which the following is a specification.

This invention has reference to ironing machines, and it relates particularly to machines of this character designed especially for use in the home.

One of the objects of the present invention is to improve the mounting and operating means for the main ironing shoe, so that it may be brought up to and fit against the material passing over the cylinder or mandrel, regardless of the bulkiness or unevenness of the material throughout the length 20 of the cylinder or mandrel.

The invention has for a further object to provide a supplemental ironing shoe and means for manipulating the same which is especially designed for ironing cuffs and 25 collars, and other small pieces on the cylinder or mandrel.

A further object of the invention is to improve the drive for the cylinder or mandrel, including a novel means of controlling 30 the operation of said cylinder or mandrel.

A further object of the invention is to improve the foot control for the main ironing shoe and to provide for its collapse or recession in the frame for shipping purposes.

That the invention may be more fully understood, reference is had to the accompanying drawings forming a part of the present description, illustrating a preferred embodiment of the invention, in which:

Fig. 1 is a front elevation of my improved ironing machine;

Fig. 2 is an end view looking in at the left hand end of Fig. 1;

Fig. 3 is an end view looking in at the right hand end of Fig. 1;

Fig. 4 is a vertical cross-section, as the same would appear, if taken on the line 4—4 Fig. 1.

Fig. 5 is a vertical cross-section, as the same would appear if taken on the line 5—5 Fig. 1;

Fig. 6 is a vertical cross-section as the

same would appear, if taken on the line 6—6 Fig. 5;

Fig. 7 is a detail front elevation of the supplemental ironing shoe, showing its inactive relation to the cylinder or mandrel;

Fig. 8 is a view similar to Fig. 7 except that the supplemental ironing shoe has been 60 lowered into engagement with the cylinder or mandrel;

Fig. 9 is a cross-section as the same would appear, if taken on the line 9—9 Fig. 8;

Fig. 10 is a cross-section, partially in plan view, as the same would appear, if taken on the line 10—10, Fig. 8.

Fig. 11 is a detail in elevation, showing the mounting for the main ironing shoe, the parts being in the position they would be in when the shoe is back and away from the cylinder or mandrel;

Fig. 12 is a view similar to Fig. 11, except that the parts have been moved to bring the main ironing shoe up to the cylinder or mandrel;

Fig. 13 is a detail cross-section, partly in elevation, of the foot control for the main ironing shoe, as the same would appear if taken on the line 13—13 Fig. 1;

Fig. 14 is a detail side elevation of the foot control showing how the same may be collapsed or folded in the frame for packing purposes;

Fig. 15 is a plan of Fig. 14, and

Fig. 16 is a detail of an adjusting means in the sliding castings for the ironing shoe.

Like characters of reference denote corresponding parts throughout the figures.

In the drawings the frame for the machine includes the end members 1, 1, having channeled inner faces, see Figs. 4, 11, and 12 and such members are joined by the connecting rods 2, 3, 4, and 6 certain of which support or carry operating parts to be hereinafter described. An additional rod 5 is provided but it does not connect the end members, being a connecting element for certain operating parts. Also connecting said end members is the receiving board 7, 100 for the ironed materials, see Figs. 1 and 4. The end members are shown supported on caster wheels 8 for the easy and convenient movement of the machine from one place to another in the home.

The cylinder or mandrel is designated 9,

of any preferred construction, altho here it is shown of hollow formation with closed ends receiving the operating shaft 10 journaled in the end members 1 arranged to be 5 driven from one end thereof. The driving means for the shaft 10 and the cylinder or mandrel comprises, preferably, an electric motor A supported on a base plate 11 secured to one of the end members 1, and said 10 motor, preferably, by means of a flexible coupling 12 is connected to a short shaft 13 carrying a worm 14, (see Fig. 5) meshing with a worm-wheel 15 on the lower end of an upstanding shaft 16, provided with a 15 worm 17 on its upper end meshing with a worm-wheel 18 carried on one end of the shaft 10, see Figs. 5 and 6. I have shown the gearing 14 and 15 enclosed within a housing 19 secured to an end member 1; a sleeve or 20 housing 20 enclosing the shaft 16, and a casting 21 enclosing the gearing 17 and 18, and other operating parts. Said housing 21 is also secured to an end member 1.

Looking at Fig. 6, the end of the shaft 10 25 is slotted as at 22 to receive a pin 23 extending transversely thru a sleeve 24 slideable on the shaft 10, and said sleeve carries the worm-wheel 18 which has an extended hub, also slotted, as at 25 into which the pin 23 30 projects. The worm-wheel 18 is held in place by the frame of the casing 21 designed for this purpose. The end of the sleeve 24 is formed with an annular groove 26 to receive studs or rollers on a bifurcated arm 35 27 of a lever 28 fulcrumed at 29 in the casing 21. Said lever has an extended plate 30 provided preferably, with ball seats 31 to receive a yieldingly held ball 32, see Fig. 5, for holding the lever 28 when it is shifted to 40 operative and inoperative positions as illustrated in full and dotted lines in Fig. 6.

In the operation of the drive for the cylinder or mandrel, assuming the motor has been connected to the source of power, by 45 shifting the lever from the dotted line position shown in Fig. 6 to the full line position in said figure, the sleeve 24 is moved inwardly carrying with it pin 23 causing it to seat itself in the slot 22 in the end of the shaft 10 which will clutch the worm-wheel 18 and sleeve 24 to the shaft, resulting in its being operated. When the lever 28 and the sleeve 24 are in the dotted line positions shown in Fig. 6, the pin 23 is withdrawn 50 from the slot 22 in the end of the shaft 10 and the gearing 17 and 18 as well as the sleeve 24 may run idle and the shaft 10 and cylinder or mandrel may remain still.

Referring now to the main ironing shoe, 55 which is designated 33, said shoe is not unlike other shoes for a similar purpose, having the concave ironing face 34 and formed with a heating chamber 35, preferably heated by the use of gas led to the shoe thru a hose 36 and controlled by a suitable regulating

valve 37, see Fig. 2. The shoe 33 is provided at each of its opposite ends with trunnions 38, and 39. The former being removably carried in bearings 40 formed in slideable castings 41, and the latter having connection with crank arms 42 having a pivotal bearing at their lower ends on the connecting rod 6. The castings 41 are preferably located within the channels of the end members 1 and at their upper ends, see Figs. 4, 70 11 and 12. These castings are formed with longitudinally disposed spaced elongated slots 43, 44, and 45. The slots 43 and 45 receive pins 46 and allow for endwise movement of said castings and said slot 44 embraces the shaft 10 so that there shall be no interference with said shaft. Said castings are also provided with a short barrel 47 and a spaced ear or extension member 48, therefrom. In the barrel is slidably carried a 80 stem 49, see Fig. 16, in which is screwed a member 50 receiving one end of a coil spring 51 with its opposite end bearing against the ear or extension 48. To the free end of each member 50 is pivotally connected a link 52, 90 which at its opposite end is pivotally connected to an arm 53 pivoted at 54 to an end member 1. And to each arm 53 there is pivotally connected at 55 a bar 56, having its lower end connected to the rod 5, and secured to said rod intermediately thereof is a casting 57, which at its lower and opposite ends is connected to the forward ends of bars 58, which at their rear ends have a 100 pivotal connection with the rod 2, see Figs. 4, 13, 14 and 15. I prefer that the connection between the casting 57 and the bars 58 be made by short spindles 59, protruding far enough thru the bars 58 to provide rests for a foot control member 60, see Fig. 13. This 105 foot control member is provided with trunnions 61 at its opposite inner corners, see Fig. 15, which fit in and slide in longitudinally disposed slots 62 provided in the bars 58. This makes it possible to slide the member 60 on the bars 58 so that the foot control may be collapsed, as it were, in the frame of the machine, and out of the way, useful especially when packing and shipping the machine. 110

In the operation of the foot control to move the ironing shoe 33 up to the cylinder or mandrel 9, assuming the parts in the assembled position shown in Figs. 4, 11, and 13, the attendant or operator by pressing down on the member 60 will oscillate the bars 58 on the rod 2 and in doing so will pull downwardly the casting 57 and the bars 56. This operation will result in an oscillation of the arms 53 and a reciprocal movement of the links 52, which as they assume an approximate horizontal position, see Fig. 12, will move the stems 49 and yieldingly move the castings 41 forwardly, and at the same time compress the springs 120 125 130

51 as the shoe 33 is brought into contact with the cylinder or mandrel 9, or the material to be ironed thereon. The sliding of the castings 41 and the arrangement of the 5 springs 51 will allow for contact of the shoe 33 with the material on the cylinder or mandrel 9 throughout its length, regardless of its evenness or unevenness, as the springs will permit all the freedom necessary in the 10 adapting of the shoe to said cylinder or mandrel. Further, it is to be observed that the construction of the mounting for the shoe 33 is such as to cause the shoe to move bodily toward the cylinder or mandrel 9 15 and then cause it to be oscillated to fit itself to the contour of said cylinder or mandrel. This is clearly apparent from an examination of Figs. 11 and 12. There it is shown, that as the castings 41 are moved forwardly 20 the trunnions 38 on the shoe 33 are moved forwardly carrying the shoe up to the cylinder or mandrel, and at the same time the cranks 42 thru the trunnion connection 39 are oscillated, and at a predetermined point 25 in the forward movement of said shoe it is caused to oscillate on the trunnion connection 39 with said cranks 42, seating itself on said cylinder or mandrel. The forward movement of the castings 41 are against the 30 tension in springs 63 connected at one end to pins 64 on the castings 41 and at their opposite ends to pins 65 on the end members 1. These springs function to normally hold the castings 41 retracted with the shoe 33 removed from the cylinder or mandrel, see Figs. 4 and 11, and act to return the shoe to this position after each operation. The 35 springs 51 function and cushion the shoe as hereinbefore explained.

40 The foot control means includes locking means for holding the shoe 33 in different positions relative to the cylinder or mandrel, and is best seen in Figs. 1, 4, and 13. On the rod 3 intermediately of the machine is secured a collar 66 provided with a tooth 67, and adapted to have a ratchet engagement with said tooth is a ratchet bar 68, carried in an upstanding position on the foot control member 60, and fulcrumed thereon at 69 and having forwardly and rearwardly arranged plate extensions 70 and 71. The former overlies the inner end of a foot lever 72 fulcrumed at 73 on the member 60, the latter having an enlarged opening 74 provided therein to allow the necessary room for the depression of said lever 72. The plate extension 71 engages a spring 75 seated on the member 60, which yieldingly holds the ratchet tooth end of the bar 68 so that it 55 will ratchet with the tooth 67 as the member 60 is depressed.

60 It will be understood, that as the member 60 is depressed to move the ironing shoe 33 toward the cylinder or mandrel 9 that the 65 spring 75 holds the bar 68 against the tooth

67 and will hold the shoe in whatever position it is moved. To release the ratchet bar 68, the operator will depress the lever 72, by pressing the toe of the foot thereon, which will result in lifting the plate extension 70 and oscillating the ratchet bar 68 from the full line position in Fig. 13 to the dotted line position in said figure. Immediately upon the release of the lever 72, however, the spring 75 will act to return the ratchet bar 68 to its operative position, thus providing a very effective controlling means for the shoe, and yet giving the operator a controlling means which is flexible enough to meet all requirements. It will be further observed that when the member 60 is collapsed in the frame the locking means is moved into and out of position therewith.

70 Referring now to the supplemental ironing shoe which is shown in Figs. 1 and 2, and best seen in Figs. 7 to 10, the same is designated 76 and is disposed transversely above one end of the cylinder or mandrel 9 and has a concave lower face 77 conforming approximately to the surface of said cylinder or mandrel, see Fig. 9. Said shoe 76 is pivotally connected with one end of a lever 78 fulcrumed on a bracket 79 secured to an end member 1 of the machine frame. This lever is preferably cast with a right angular chambered end member 80 carried within the shoe 76, see Figs. 9 and 10 and forms the axle on which the shoe is journaled, preferably by studs 81 carried thru the end walls of the shoe and centered in the ends of said member 80. The shoe has its rear wall slotted, as at 82 to receive the lever 78, and to provide an air inlet opening into the shoe; and a cap or cover plate 83 for the shoe enables the placing and removal of the lever 78 and the member 80 therewithin. The wall of the member 80 is perforated as at 84 which act as jets for the escaping gas, which when lighted, heats the shoe. Gas is admitted to the member 80 thru a chamber 85 in the lever 78, which is in communication with a suitable valve 86 controlling the supply fed thru the main feed conduit or hose 36, as will be understood.

75 The lever 78 may be actuated, in a manner to be explained, to lower and raise the shoe 76, and the shoe being pivoted on the end of the lever, when it comes into contact with the cylinder or mandrel 9, or the piece thereon to be ironed, will adapt itself thereto. The pivoting of the shoe will also allow for any wear by reason of constant use, and insure its fitting itself to the cylinder or mandrel. The shoe is normally held raised 120 by a coil spring 87 connected to the outer end of the lever 78 and to an end member 1 of the frame, and returns the shoe to its raised inoperative position, after actuation.

125 The means for actuating the lever 78 and shoe 76, comprises a foot lever 88 fulcrumed 130

on the cross-rod 3, see Figs. 1 and 2, being held in proper position therein by collars 89 and to the inner end of said foot lever is pivotally connected the lower end of a connecting rod or bar 90, which at its upper end is pivotally connected to the lever 78. By depressing the foot lever 88 and raising the rod or bar 90 and oscillating the lever 78, the shoe 76 will be lowered into position 10 to seat itself on the cylinder or mandrel. As soon as the foot lever 88 is released, the spring 87 acts immediately to return the parts to their inoperative positions.

What I claim is:

15. 1. In an ironing machine, a frame, a cylinder thereon, a pair of members, means for connecting the members to the frame for slideable movement relative thereto, a shoe, means for mounting the shoe on said members to cause same to partake of the sliding movement of the members and to enable the shoe to have pivotal movement independent of the sliding movements of the members, means connected to the members to slide same, and independent means connected to the frame and pivotally connected to the shoe for effecting pivotal movement of the shoe at a predetermined point in the sliding movements of the members.
20. 2. In an ironing machine, in combination, an ironing cylinder, a pair of sliding frames, an ironing shoe supported to be moved bodily by said frames, pivoted members with which the shoe has a connection, whereby 25 the shoe will be oscillated to adapt it to said cylinder following its bodily movement, a spring on each frame to cushion the seating of the shoe against the cylinder, a foot control for actuating said frames, and spring 30 means to return the frames and shoe after each operation.
35. 3. In an ironing machine, in combination, a frame, an ironing cylinder journaled therein, an ironing shoe movable toward and from the cylinder, a foot lever, a movable support for said lever, whereby it may be collapsed in the frame, operating connections between said lever and said shoe, means on the lever having a ratchet locking relation 40 with a frame part, and foot actuating means on said lever for releasing said locking means.
45. 4. In an ironing machine, in combination, a main frame an ironing cylinder journaled therein, slideable frames at each end of said main frame, an ironing shoe, means supporting said shoe in said frames, pivoted supports with which said shoe is connected, a foot lever, operating connections between said lever and said frames, coacting means on the lever and main frame to lock the frame and shoe in different positions, and foot operating means on the lever to release said locking means.
50. 5. In an ironing machine, in combination, 55

with an ironing cylinder and a main ironing shoe lying parallel to said cylinder and movable toward and from said cylinder, of a supplemental ironing shoe disposed above one end of said cylinder, a lever support for 70 said supplemental shoe, and foot actuating means for operating said lever.

6. In an ironing machine, in combination with an ironing cylinder and a main ironing shoe lying parallel to said cylinder and 75 movable toward and from said cylinder, means also on said foot means for releasing said locking means, of a supplemental ironing shoe disposed above one end of said cylinder, a pivoted support for said supplemental shoe, and foot means to operate said pivoted support, and spring means for lifting the supplemental shoe into inoperative position away from said cylinder.

7. In an ironing machine, in combination, 80 a frame, an ironing cylinder, an ironing shoe movable toward and from said cylinder, a foot operated member having a slideable connection with said frame, operating connections between said member and said shoe, an 85 upstanding ratchet bar on said member, a tooth on the frame engageable by said bar and a foot operated lever on said member for releasing said ratchet bar.

8. In an ironing machine, in combination, 90 a frame, an ironing cylinder, an ironing shoe movable toward and from said cylinder, a foot operated member, operating connections between said member and said shoe, a ratchet tooth bar pivoted on said member, a tooth 100 on the frame engageable by said bar, yielding means for holding the bar in engagement with said tooth, and a foot operated lever on said member to actuate said bar and to release it from engagement with said tooth.

9. In an ironing machine, in combination, 105 an ironing cylinder, a pivotally supported member located outside the frame of the machine and at one end of the cylinder, an ironing shoe carried by said member and 110 normally disposed above one end of said cylinder, a foot operated lever, and operating connections between said lever and said pivotally supported member.

10. In an ironing machine, in combination, 115 an ironing cylinder, an ironing shoe located at one end and above said cylinder and having a heating chamber, a pivoted member having a part within said shoe forming the axle on which said shoe is pivoted, means yieldingly holding the member and shoe elevated, and means to actuate said member to move it toward the cylinder, the pivotal connection between shoe and member permitting the shoe to adapt itself to the 120 contour of the cylinder.

11. In an ironing machine, in combination, 125 a pair of slideable frames each having trunnion sockets, an ironing shoe, trunnions thereon journaled in said frame sockets, piv- 130

oted crank arms connected to said shoe, levers operatively connected with said frames, a foot operating means, and operating connections between said foot operating means and said levers.

12. In an ironing machine, in combination, a pair of slidable frames each having trunnion sockets, yielding means to hold the frames retracted, an ironing shoe having 10 trunnions journaled in said frame sockets,

pivoted crank arms connected to said shoe, a lever associated with each frame, a link connected to each lever and yieldingly connected to each frame, a foot operating means, and operating connections between said foot 15 operating means and said levers.

In witness whereof, I have hereunto affixed my hand this 22 day of February, 1921.

ALPHEUS W. ALTORFER.
